UNITED STATES PATENT OFFICE.

WILLIAM H. SMITH, OF FLORENCE, MASSACHUSETTS.

TOOTH-BRUSH.

SPECIFICATION forming part of Letters Patent No. 396,898, dated January 29, 1889.

Application filed June 4, 1888. Serial No. 275,948. (No model.)

To all whom it may concern:

Be it known that I, WILLIAM H. SMITH, of Florence, in the county of Hampshire and State of Massachusetts, have invented a new and Improved Tooth-Brush, of which the following is a specification, reference being had to the annexed drawings, forming a part thereof, in which—

Figure 1 is a side elevation of my improved tooth-brush. Fig. 2 is a plan view showing the brush folded into one-half of the handle, with the handle open. Fig. 3 is a transverse section taken on line xx in Fig. 1, and Fig. 4 is a transverse section taken on line yy in Fig. 1.

Similar letters of reference indicate corresponding parts in all the views.

The object of my invention is to provide a tooth-brush with a hollow handle, in which the brush may be inclosed when not in use, to render the brush portable, and to protect it from injury.

My invention consists in the combination, with a tooth-brush, of a hollow handle made in two parts hinged together and adapted to receive the brush, the brush being pivoted in one half of the handle.

The brush A is formed of the back a , the bristles b , and the shank c . The handle B consists of two like parts, d d' , connected by hinges e , the part d of the handle being provided with a spring-catch, f , adapted to engage an inwardly-projecting lug, g , in the opposite part, d' . A push-pin, h , is inserted in

the part d' above the lug g and adapted to 35 disengage the spring-catch f from the said lug. The halves d d' of the handle are preferably tapered, and from the smaller end inward they are provided on their adjoining faces with semicircular grooves i , adapted to 40 receive the shank c of the brush A, and the end of the said shank c is pivoted in the groove i of the half d' .

When the brush A is unfolded and the handle B is closed, as shown in Fig. 1, the brush 45 is arranged for use. When the brush is not in use, it is folded into the handle, as shown in Fig. 2, and the handle is shut so as to inclose the brush.

Having thus described my invention, I claim 50 as new and desire to secure by Letters Patent—

1. The combination, with the brush A, provided with the short shank c , of the hollow handle B, formed of the halves d d' , connected by hinges and adapted to receive the 55 brush, substantially as described.

2. The combination of the hollow handle B, formed of the similar halves d d' , having semicircular grooves i , the hinges e , connecting the halves, the spring-catch f , the push-pin h , 60 and the brush A, provided with the shank c , pivoted in the half d' , substantially as described.

WILLIAM H. SMITH.
